CARDIAC AND THORACIC SURGERY INSTRUMENT

Walter C. Ashcraft, Sacramento, Calif.
(933 Main St., Lander, Wyo. 82520)

Filed Mar. 1, 1974, Ser. No. 447,311

Term of patent 14 years

Int. Cl. D24—02

U.S. CL. D83—12 R

FIG. 1

FIG. 2

FIG. 3

FIG. 4

FIG. 5

FIG. 1 is a side elevational view of a cardiac and thoracic surgery instrument showing my new design, the selectively positionable longitudinally slidable fulcrum member being shown in substantially mid-position, the opposite side being in mirror symmetry;

FIG. 2 is a top plan view;

FIG. 3 is a bottom plan view;

FIG. 4 is an elevational view of the front, sternal-engaging end; and,

FIG. 5 is an elevational view of the after, handle end.

I claim:

The ornamental design for a cardiac and thoracic surgery instrument, as shown and described.
